UNITED STATES PATENT OFFICE

122,046

DESIGN FOR A GARMENT DISPLAY STAND OR SIMILAR ARTICLE

Sidney Ring, New York, N. Y.

Application January 16, 1940, Serial No. 89,501

Term of patent 3½ years

To all whom it may concern:

Be it known that I, Sidney Ring, a citizen of the United States, residing in New York city, in the county of New York, and in the State of New York, have invented a new, original, and ornamental Design for a Garment Display Stand or Similar Article, of which the following is a specification, reference being had to the accompanying drawing, forming part thereof:

In the drawing:

Figure 1 is a side elevational view of a garment display stand or similar article, showing my new design; and

I claim:

The ornamental design for a garment display stand or similar article, substantially as shown.

SIDNEY RING.
